STORM SASH FASTENER

George Frederick Schuster, Waterbury, Conn., assignor to The Stanley Works, New Britain, Conn., a corporation of Connecticut

Application May 24, 1932, Serial No. 613,205

7 Claims. (Cl. 292—276)

The present invention relates to fasteners or stays, and finds particular application in connection with storm sashes for windows, it being understood, however, that the invention is not limited to that particular application.

An object of the invention is to provide an improved device of this character which will not strike, or interfere with, in any way, the lower sash of the window frame, or interfere with the closing of the storm sash.

Another object of this invention is to provide an improved device of this character which will admit of a number of adjustments which are limited only by the length of the stay member.

A still further object of the present invention is to provide a device of this character which will securely hold the storm sash in adjusted position so that it will not inadvertently close and will prevent the storm sash from rattling.

Another aim of this invention is to provide a device of this character which is cheap to manufacture, can be readily assembled, which is strong and durable, and will not be apt to get out of order.

Other objects will be in part obvious, and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawing, wherein is shown, for illustrative purposes, one of the embodiments which the present invention may take;

Fig. 1 is a vertical transverse section through a window casing having a storm sash and showing my improved device attached thereto;

Fig. 2 is a detail view showing the storm sash with my improved device attached thereto in closed position;

Fig. 3 is a side elevation of my improved device; Fig. 4 is an edge elevation of the same;

Fig. 5 is an end view of my improved device; and Fig. 6 is a view partly in section of my improved device.

In order that the hereinafter detailed description may be more clearly and readily understood, it may be briefly stated that my fastener is shown as applied to a window, generally designated A, which has secured thereto and exteriorly thereof a storm sash B. My improved fastener, generally designated C, is pivotally secured to the window frame A and storm sash B.

Referring more particularly to the drawing, the

window frame A is of the usual construction and is provided with a sill 10, a lintel 11, and a pair of vertically disposed styles or side members one of which is shown in the drawing and designated by the numeral 12. The styles or side members are each provided with guide strips 13, 14, and 15. The lower sash 16 is supported in the window frame for vertical movement therein between the guide strips 13 and 14, while the upper sash 17 has vertical movement between the guide strips 14 and 15. Pivotedly secured to the exterior portion of the lintel 11 of the window frame A, as by separable hinges 18, is the storm sash B. This storm sash B is shown as comprising the transverse strips 19 and the vertical strips 20, 15 only one of which is shown in the drawing. This storm sash B is adapted to have swinging movement exteriorly of and towards and away from the frame A.

In order to maintain the sash B in its extreme 20 inner and outer positions and in all intermediate positions, I have provided a fastener C. This fastener C comprises a stay 21 which is pivotally secured at one end thereof by means of a rivet 22 to a bracket 23 which in turn is fixedly secured to one of the vertical uprights 20 of the storm sash B. The stay 21, at its pivoted end, is straight for a short distance and then the stay is bowed inwardly towards the sash 16 when the fastener is in closed position. The curvature of the bowed portion is generally in the form of an arc, as at 27, but gradually decreases, as at 28, toward the free end of the stay. The free end of the stay is bent over at substantially right angles to the main portion of the stay and laterally there- 30 to to provide a handle 29 by means of which the stay is moved and the handle 29 also acts as a stop to prevent the accidental withdrawal of the stay from a guide member 30 in which the stay is adapted to slide.

The object of providing the stay 21 with a bowed portion is to effect a substantially rectilinear movement of the free end of the stay as it slides through the guide member 30, rather than a pronounced arcuate movement produced if the stay were straight. This substantially rectilinear movement of the free end of the stay is substantially parallel with the plane of the sash 16 so that the free end of the stay will not strike against, or in any way interfere with, the lower sash 16 during closing movements of the storm sash B and when the latter is fully closed. Also, the arrangement is such that the stay does not interfere with the closing of the storm sash.

The guide member 30 may be made from a sub-

stantially rectangular piece of metal which is bent to C-shape and comprises a body or connecting portion 31, a pair of spaced parallel sides 32 and 33 disposed at substantially right angles to said body portion 31, and a pair of opposed in-turned flanges 34 and 35 extending from the free ends of, and substantially at right angles to, the respective sides 32 and 33. The free inner ends of the flanges 34 and 35 are spaced apart to provide an entrance slot 36 for the stay 21. The width of the slot 36 is slightly greater than the width of the stay 21, to facilitate the introduction of the stay into the guide member 30. The guide member 30 is pivotally secured to a bracket 37 by means of a rivet 38 passing through aligned openings in the bracket and the side 32 of the member 30 respectively. The rivet 38 may be fixedly secured to either the bracket 37 or the member 30 but in the drawing is shown as fixed to the bracket as at 39. The rivet is provided with a circular collar 40 intermediate its ends and with an enlarged circular head 41 at its end opposite to the end 39. The head 41 constitutes a jaw having its free face substantially flat. The opening in the side 32 of the member 30 is substantially circular and has a reduced bore, as at 42, which receives the collar 40 of the rivet and an enlarged bore as at 43, which receives the head 41 of the rivet. The sides of the reduced bore of the side 32 of the member 30 engages the inner face of the head 41 of the rivet and thus prevents the separation of the bracket 37 and the member 30 but at the same time there is sufficient looseness between the sides of the opening in the side 32 of the member 30 to permit the member 30 to freely pivot about the rivet 38 as an axis. The bracket 37 is fixedly secured to one of the styles or side members 12 of the window frame A, preferably between the guide strips 14 and 15 by means of fastening elements 44 passing through openings 45 in the bracket. The side 33 of the guide member 30 is provided with a threaded opening 46 in alignment with the opening in the side 32, and the threaded opening 46 is adapted to receive a screw 47 which extends through said threaded opening and beyond each face of the side 33 of the member 30. Secured to the inner end of the screw 47 and opposed to and spaced from the head 41 of the rivet 38 is a movable jaw member 48 which, in the present instance, is illustrated as a flat disk. The jaw 48 cooperates with the head 41 of the rivet 38 to clamp the stay 21 therebetween. The outer end of the screw 47 is provided with a finger piece 49 by means of which the screw is rotated to move the jaw 48 towards and away from the head 41 of the rivet 38.

It will be noted from Fig. 5 that the head 41 of the rivet 38 is not in alignment with the free end of the flange 34 but is offset therefrom toward the side 32 of the member 30 a distance equal to substantially the width of the stay 21, so that when the stay 21 is clamped between the rivet head 41 and the jaw 48, it is out of line with the slot 36 in the guide member 30, and even when the jaw 48 is backed off sufficiently to loosen the grip upon the stay 21 the latter will fall upon the flange 34 and be retained thereby in the guide member 30. At this time, the jaw 48 will be disposed in line with the slot 36 and will, therefore, aid in retaining the stay in the member 30. However, when it is desired to remove the stay from the member 30, the screw 47 and jaw 48 may be further backed off until the jaw 48 is clear of the slot 36 at which time the stay may be

moved laterally and then passed through the slot 36 outwardly of the guide member.

The operation of the device is as follows: Assuming that the bracket 23, with the stay 21 pivotally carried thereby, has been secured to the frame of the storm sash B and the bracket 37, with the guide member 30 pivotally carried thereby, secured to the window frame A as shown in Figs. 1 and 2, the guide member is turned on its pivot so that the entrance slot 36 faces the edge of the stay 21 and the jaw 48 is backed off clear of the slot 36. The stay is then passed through the slot and the jaw 48 moved inwardly to block the opening 36. The storm sash B is then adjusted to the desired position after which the screw 47 is rotated until the jaw 48 clamps the stay between itself and the head 41 of the rivet 38. As the stay moves through the member 30 during the adjustment of the sash B, the movement of the free end of the stay, due to its bowed formation, will be a substantially rectilinear one which is substantially parallel to the plane of the sash 16 of the frame A rather than a movement in an arc which would be the case were the stay straight throughout its length. Due to the direction of movement of the stay, it is apparent that during movement of the stay and when brought to rest the free end of the stay will occupy a position outwardly of the sash 16 so that, regardless of the position of the storm sash B and the stay 21, the lower sash 16 may be in a lowered closed position, as shown in Figs. 1 and 2.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a fastener for a storm sash of a window frame, an adjustable stay adapted to be secured to the storm sash, a guide member for said stay and having an entrance slot at one side, means for pivotally mounting said guide member on the window frame, a fixed jaw within said guide member, and a movable jaw carried by said guide member in opposed relation to said fixed jaw, said guide member having a portion extending beyond the face of said fixed jaw whereby the stay is prevented from falling out through the slot in the guide member when the movable jaw is slightly disengaged from said stay.

2. In a fastener for a storm sash of a window frame, an adjustable stay adapted to be pivotally secured to a storm sash and comprising a strip of flat metal, a bracket adapted to be secured to the window frame, a guide pivotally secured to said bracket and comprising a piece of metal bent generally into rectangular form and having a slot at one side through which the stay is adapted to be inserted, a fixed jaw within said guide member and having its jaw face offset inwardly of said slot, a movable jaw opposed to said first jaw, and a screw threaded in said guide member and carrying said second mentioned jaw.

3. In a fastener for a storm sash of a window frame, an adjustable stay adapted to be secured

to said storm sash, a guide member for said stay and having an entrance slot for said stay, means for pivotally mounting said guide member on said window frame, a movable jaw carried by said 5 guide member and adapted to cooperate with said pivot means to hold said stay in adjusted position, said guide member having a portion overhanging the inner end of said pivot means, whereby the stay is prevented from falling out through the slot 10 in the guide member when the movable jaw is slightly disengaged from said stay, and means for moving said jaw.

4. In a fastener for a storm sash of a window frame, an adjustable stay secured to said storm 15 sash, a guide member for said stay, means for pivotally mounting said guide member on said window frame, a movable jaw carried by said guide member and adapted to cooperate with said pivot means to hold said stay in adjusted position, 20 said guide member being of C-shape and having a pair of inturned spaced apart flanges which provide therebetween an entrance slot for the stay, one of said flanges overhanging the inner end of said pivot means whereby said stay 25 will fall upon said flange and be retained within said guide member when the movable jaw is slightly backed off, and means for moving said jaw.

5. In a fastener for a storm sash of a window 30 frame, an adjustable stay secured to said storm sash, a guide member for said stay, means for pivotally mounting said guide member on said window frame, a movable jaw carried by said guide member and adapted to cooperate with said 35 pivot means to hold said stay in adjusted position, said guide member being of C-shape and having a pair of inturned spaced apart flanges which provide therebetween an entrance slot

for the stay, one of said flanges overhanging the inner end of said pivot means and being in line with said stay, and means for moving said jaw, said jaw having an initial backed off position in which it blocks said entrance slot and being adapted to be further backed off until it clears the entrance slot. 5

6. In a fastener for a storm sash of a window frame, an adjustable stay pivoted at one end to the storm sash and having its other end free, 10 said stay having an inwardly bowed portion, a guide pivoted against linear movement to the window frame and cooperating with said bowed portion to guide the stay, and clamping means carried by said guide for holding said stay in 15 adjusted position, said bowed portion of said stay being so shaped and arranged that the free end of said stay has a relatively small lateral movement compared to its vertical movement, said lateral movement being limited between the 20 planes of the window sash and the storm sash as the stay slides through said fixed guide.

7. In a fastener for a storm sash of a window frame, an adjustable stay pivoted at one end to said storm sash and having its other end free, 25 said stay having a bowed portion the curvature of which gradually decreases towards the free end of the stay, a guide member pivotally secured against linear movement to the window frame and adapted to embrace said stay to co- 30 operate with, and automatically accommodate itself to, said bowed portion to guide the stay in its movements to prevent the same from striking the lower sash of the window, and means associated with said guide for holding the stay in 35 adjusted position.

GEORGE FREDERICK SCHUSTER.
